O. E. LONGSDORF,
CONTACT FOR SUBSURFACE ELECTRICAL RAILROAD SYSTEMS,
APPLICATION FILED SEPT. 24, 1915.

1,178,247.

Patented Apr. 4, 1916.

UNITED STATES PATENT OFFICE.

OWEN E. LONGSDORF, OF CHICAGO, ILLINOIS.

CONTACT FOR SUBSURFACE ELECTRICAL-RAILROAD SYSTEMS.

1,178,247.

Specification of Letters Patent.

Patented Apr. 4, 1916.

Application filed September 24, 1915. Serial No. 52,463.

To all whom it may concern:

Be it known that I, OWEN E. LONGSDORF, a citizen of the United States, and a resident of the city of Chicago, county of Cook, and State of Illinois, have invented certain new and useful Improvements in Contacts for Subsurface Electrical-Railroad Systems, of which the following is a specification.

My invention relates to improvements in subsurface electrical railroad system contacts, and has for its object the production of a contact of this character which will be of economical construction, one which will be adapted to effectually and positively 15 break the electrical connection between the power conductor and the exposed rail except during the passing of a train, one which, in establishing connection between the power conductor and the exposed rail, 20 will be free from arcing, and one which generally will be highly efficient in use.

Other objects will appear hereinafter.

With these objects in view, the invention consists in the combinations and arrangements of parts hereinafter described and 25 claimed.

The invention will be best understood by reference to the accompanying drawing forming a part of this specification, and in 30 which,

Figure 1 is a top plan view of a contact device embodying the invention, Fig. 2 is a vertical longitudinal section through the device, and Fig. 3 is an enlarged section 35 taken on line $x-x$ of Fig. 2.

The preferred form of construction, as illustrated in the drawing, comprises a block or holder 1 of cement or other suitable insulating material. Formed in the member 40 1 is a plurality of spaced upwardly opening cylindrical recesses 2 in each of which is mounted an upwardly opening receptacle 3 of porcelain or other suitable insulating material.

45 In each receptacle 3 is arranged a metallic contact ring 4 with which is connected a conductor wire 5 leading to the power conductor which extends longitudinally of the track in connection with which the system 50 is employed below the surface of the ground or protected against external contact. The contact ring 4 is held in position in the receptacle 3 by means of sleeves 6 and 6' of porcelain or other suitable insulating material.

A cylindrical opening 7 is thus formed through the parts 4, 6 and 6' at the upper end of which is provided a contact member 8 of carbon, or other suitable conducting material, the member 8 being sealed in the upper end of receptacle 3 by means of a layer 8' of suitable insulating material. Each member 8 is connected by means of a conductor wire 9 with the depending flange 10 of a contact rail 11 which is arranged at 60 the upper side of member 1 extending longitudinally thereof. The upper end of member 1 is formed with a longitudinally extending slot 12 for the reception of the flange 10. The upper end of rail 11 is of a 65 width slightly greater than the diameter of recesses 2 in order to close the same and the upper portion of said rail is convexed or bowed upwardly to permit of slight yielding of the same in the contact therewith of 70 the contact shoe or brush carried by the train in conjunction with which the system is employed. In installing a system in connection with a railroad, the blocks 1 are arranged parallel with the track rail end to 75 end, and to prevent contact of the rail members 11 of adjacent blocks 1, said rail members are made shorter than the blocks so that said rail members terminate a short 80 distance from the ends of the blocks and 85 thus positively prevent contact between the ends of adjacent rail members.

Arranged in the opening 7 in each receptacle 3 is a snugly fitting armature 13 of Norway iron or other suitable conducting 90 material which is adapted for free vertical movement in said opening. When said armature is at its upper terminal of movement, balls 14, loosely mounted in an annular groove 15 formed in the inner edge of 95 contact member 4, will engage in an annular groove 16 formed adjacent the lower end of said armature and thus serve to establish 100 electrical connection between the contact members 4 and 8. A plurality of balls 14 is employed coöperating with each armature 13, said balls moving automatically by gravity into and out of engagement with the corresponding groove 16 in the vertical 105 movement of the armature. The employment of a series of balls in connection with each armature which, when the latter is at its upper terminal of movement, engage partly with the member 4 and partly with the armature 13, results in a very efficient 110

electrical connection between the contact members 4 and 8.

Arranged in the lateral surface of each armature 13 intermediate the ends thereof is a layer 17 of insulating material adapted when the armature is at its lower terminal of movement to register with the balls 14 and thus break the electrical connection between the armature and the contact member 4. Electrical connection between the armature and the contact member 8 is of course broken upon downward movement of said armature but the provision of the insulating member 17 affords additional means for insuring positively the breaking of electrical connection between the contact members 4 and 8 through insulation of the armature from the contact member 4, when said armature is at its lower terminal of movement. The insulating member 17 is so positioned that, in the upward movement of the armature, the balls 14 contact with said armature before the upper end of the latter contacts with the contact member 8. With this arrangement, arcing which is one of the chief objections in devices of this character in making the connection of the contact rail with the power conductor, is positively prevented.

In the operation of the device, it will be seen that normally the electrical connection between the contact rail 11 and the power conductor used in connection with the system is broken. The device is designed for use in connection with trains equipped with contact brushes or shoes which are magnetic and which thus serve the double function of magnets and conductors. In the passage of a train, the magnetism of the contact brush or shoe of the train serves to attract the armatures 13 upwardly thereby resulting, when said armatures reach their upward terminals of movement, in the electrical connection between the contact rail 11 and the power conductor which is connected with the conductor wire 5, as will be readily understood. Electrical connection is thus afforded between the power conductor and the brush or shoe of the train with the result of supplying the necessary power or current for the propulsion of the train. After the train has passed, the armatures 13 drop downwardly by gravity to their lower terminals of movement with the result of breaking electrical connection between the contact rail 11 and the power conductor.

In the manufacture of the devices, the parts carried by each of the members 3 are first assembled in the latter. The conductor wires 9 are then connected with the flange 10 of the conductor rail whereupon said parts are placed in the block 1 in the positions shown. A suitable molten sealing insulating material is then poured into the

upper ends of the recesses 2, access to said recesses for this purpose being gained through the ends of slot 12.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A sub-surface electrical railroad system contact comprising two spaced contact members; a movably mounted armature adapted in one position to establish electrical connection between said contact members; and an insulating element on said armature adapted, when said armature is in another position, to register with one of said contact members and break said electrical connection, substantially as described.

2. A sub-surface electrical railroad system contact comprising two spaced contact members; a movably mounted armature adapted to be attracted to one position to establish electrical connection between said contact members, movement of said armature from such position effecting disengagement thereof from one of said contact members; and an insulator on said armature for insulating the same from the other of said contact members in the movement of said armature from engagement with said first mentioned contact member, said armature engaging with one of said contact members before the same engages with the other contact member in the movement of said armature to operative position, substantially as described.

3. A sub-surface electrical railroad system contact comprising a receptacle; two spaced contact members in said receptacle insulated from each other; an armature mounted for reciprocatory movement in said receptacle and adapted to be attracted to one position to establish electrical connection between said contact members, movement of said armature from such position effecting disengagement thereof from one of said contact members; and an insulator on said armature for insulating the same from the other of said contact members in the movement of said armature from engagement with said first mentioned contact member, substantially as described.

4. A sub-surface electrical railroad system contact comprising a receptacle having an elongated guide opening therein; a contact member arranged at one end of said opening; a second contact member register-

- ture, when in said position, engaging also with said second mentioned contact member to establish electrical connection between said contact members; and an insulator on 5 said armature adapted, when the latter moves from engagement with said first mentioned contact member, to effect disengagement thereof also from said second mentioned contact member, said armature, in 10 the movement thereof to operative position, engaging with said second mentioned contact member before the same engages with said first mentioned contact member, substantially as described.
- 15 10. A sub-surface electrical railroad system contact comprising a receptacle having an elongated guide opening therein; a contact member arranged at one end of said opening; a second contact member registering 20 with the side of said opening and insulated from said first mentioned contact member; an armature mounted for reciprocation in said opening and adapted to be attracted by said first mentioned contact member to a 25 position in engagement therewith, said armature, when in said position, engaging also with said second mentioned contact member to establish electrical connection between said contact members; an insulator on said 30 armature adapted, when the latter moves from engagement with said first mentioned contact member, to effect disengagement thereof also from said second mentioned contact member; a contact rail permanently 35 electrically connected with said first mentioned contact member; and a power conductor permanently electrically connected with said second mentioned contact member, substantially as described.
- 40 11. A sub-surface electrical railroad system contact comprising a body having an upwardly opening recess therein; a receptacle arranged in said recess having an elongated guide opening therein; a contact member arranged at one end of said opening; a second contact member registering 45 with the side of said opening and insulated from said first mentioned contact member; an armature mounted for reciprocation in 50 said opening and adapted to be attracted by said first mentioned contact member to a position in engagement therewith, said armature, when in said position, engaging also with said second mentioned contact 55 member to establish electrical connection between said contact members; an insulator on said armature adapted, when the latter moves from engagement with said first mentioned contact member, to effect disengagement 60 thereof also from said second mentioned contact member; a contact rail at the upper side of said body; a depending flange on said rail engaging a slot provided in the upper side of said body and being 65 permanently electrically connected with said first mentioned contact member; and a power conductor permanently electrically connected with said second mentioned contact member and extending exteriorly of said body, substantially as described.

70 12. A sub-surface electrical railroad system contact comprising a body having an upwardly opening recess therein; a receptacle arranged in said recess having an elongated guide opening therein; a contact member arranged at one end of said opening; a second contact member registering with the side of said opening and insulated from said first mentioned contact member; an armature mounted for reciprocation in 75 said opening and adapted to be attracted by said first mentioned contact member to a position in engagement therewith, said armature, when in said position, engaging also with said second mentioned contact member to establish electrical connection between said contact members; an insulator on said armature adapted, when the latter moves from engagement with said first mentioned contact member, to effect disengagement 80 thereof also from said second mentioned contact member; a contact rail at the upper side of said body; a depending flange on said rail engaging a slot provided in the upper side of said body and being 85 permanently electrically connected with said first mentioned contact member, the upper portion of said contact rail closing the upper end of said recess; and a power conductor permanently electrically connected 90 with said second mentioned contact member and extending exteriorly of said body, substantially as described.

95 13. A sub-surface electrical railroad system contact comprising a body; a contact rail mounted upon the upper side of said body; a power conductor entering the lower portion of said body and normally insulated from said rail; and magnetically controlled means for electrically connecting 100 said power conductor with said rail, the upper end of said rail being bent back upon itself to form a resilient contacting portion, substantially as described.

105 In testimony whereof I have signed my name to this specification in the presence of two subscribing witnesses.

OWEN E. LONGSDORF.
